HAIR DRYER

Donald W. Haarman, Bloomington, Ill.

Application April 15, 1957, Serial No. 45,744

Term of patent 14 years

(Cl. D86—10)

Fig. 2.

Figure 1 is a perspective view of the hair dryer, showing my new design, the view looking toward the front of the dryer and showing one side thereof, and

Figure 2 is a perspective view looking toward the rear and showing the other side of the dryer.

I claim:

The ornamental design for a hair dryer, as shown.
